UNITED STATES PATENT OFFICE.

CHARLES B. GIFFORD, OF TOLEDO, OHIO.

DESIGN FOR A LETTER-DEPOSIT MAILING-CASE.

SPECIFICATION forming part of Design No. 29,888, dated December 27, 1898.

Application filed November 28, 1898. Serial No. 697,703. Term of patent 14 years.

To all whom it may concern:

Be it known that I, CHARLES B. GIFFORD, a citizen of the United States, residing at Toledo, in the county of Lucas and State of Ohio, have invented and produced a new and original Design for a Letter-Deposit Mailing-Case, of which the following is a specification.

My invention relates to a new and original design for letter-deposit mailing-cases; and the leading feature consists in the case having the shape shown and provided with a number of compartments, as hereinafter fully described and claimed.

In the accompanying drawing the figure represents a perspective view of a letter-deposit mailing-case constructed according to my design.

In the said drawing the reference-letter D designates a rectangular case formed with an

ornamental molded portion at the top or upper end. Said case is provided with a number of compartments A, formed by longitudinal parallel partitions E. At one side or end of the compartments A are a number of compartments B, formed by horizontal and vertical partitions, and at the bottom of the case, below the compartments A, is a drawer C.

What I claim is—

The design for a letter-deposit mailing-case substantially as herein shown and described. 30

In testimony whereof I have hereunto set my hand in presence of two subscribing witnesses.

CHARLES B. GIFFORD.
